UNITED STATES PATENT OFFICE.

GEORGE W. WRIGHT, OF LOS ANGELES, CALIFORNIA.

PUMP.

1,419,436.

Specification of Letters Patent. Patented June 13, 1922.

Application filed April 25, 1921. Serial No. 464,138.

To all whom it may concern:

Be it known that I, GEORGE W. WRIGHT, a citizen of the United States, residing in Los Angeles, county of Los Angeles, State of California, have invented new and useful Improvements in Pumps, of which the following is a specification.

This invention has to do with a pump and more particularly with a well pump of the general type used in oil wells, etc., and an object of the invention is to provide improvements in a pump of this character such as will render it effective and durable.

In pumping oil from wells great difficulty is experienced in keeping the working parts of the pumps in good operating condition and in keeping the plungers of the pumps packed so that the pumps will be effective. These difficulties are due mainly by the working parts becoming quickly worn by sand and gritty substances operating under great pressure; or parts of the pump being sprung or strained beyond the point that the construction will stand; but more particularly to the absence of means for effectively and properly renewing and keeping packing at the necessary parts.

A particular feature of the present invention is the provision of a pump which will operate in a well under ordinary working conditions without parts becoming excessively worn or scored. The invention provides a pump structure wherein certain of the parts are self centering and are not rigidly and immovably arranged. If strains come upon the plunger to temporarily flex it slightly out of shape the packing through which it is operating conforms thereto and will not bind on it to cause freezing of the pump or injury to its parts.

A distinctive feature of the invention is the provision of means for the storage of reserve packing away from contact with the plunger, and for keeping the operative packing effectively on the plunger. By the invention the packing is kept under uniform pressure along the plunger, thereby causing it to wear evenly and uniformly, and upon wearing of the packing new packing is fed into place so that the joint is properly maintained.

The various objects and features of the invention will be best and more fully understood from the following detailed descrip-

tion of a specific preferred embodiment of the invention throughout which reference is had to the accompanying drawings, in which—

Fig. 1 is a view of the pump provided by the present invention, showing it as it would appear in the typical well casing; Fig. 2 is an enlarged detail sectional view of the upper portion, or half, of the pump; and Fig. 3 is an enlarged detailed sectional view similar to Fig. 2 of the lower portion, or half, of the pump.

Throughout the drawings numeral 10 designates a well casing in which is arranged the pump 11. The pump 11 is carried at the lower end of a tube 12 and is adapted to be operated by a sucker rod 13. The pump 11 comprises, generally, a pump barrel 14, a plunger 15 carried in the pump barrel 14 by suitable packing, a casing 16 mounted at the lower end of the pump barrel 14 to form a pump chamber, and suitable inlet and discharge valves. The pump barrel 14 is carried or supported by the tube 12, while the plunger 15 is supported or carried by the sucker rod 13. The pump is adapted to be lowered into the casing 10 by lowering of the tube 12 and sucker rod 13 is adapted to be operated by up and down movement of the sucker rod. When the sucker rod 13 is at the upper end of its movement, or stroke, the plunger 15 is at the upper end of its stroke, or, is in the position shown in Fig. 1 of the drawings. With the plunger at the upper end of its stroke the sucker rod socket 17, which connects the plunger 15 and sucker rod 13, is at, or near, the extreme upper end of the pump barrel, or is in the vicinity of the coupling 18 which connects the uppermost sections 19 of the pump barrel with the tube 12, while the lower end of the plunger is at, or close to, the lower end of the pump barrel, or is near the point of connection between the lower end of the pump barrel and casing 16. When the sucker rod 13 is at the lower end of its movement, or stroke, the plunger 15 is at the lower end of its stroke and the sucker rod socket 17 is at the lower end of the section 19, or is near the coupling 20 which connects the sections 19 and 21 of the pump barrel, while the lower end of the plunger 15 is at, or near, the lower end of the casing 16. The intake valve 22 of the pump is mounted in the

lower end of the casing 16, while the discharge valve 23 is mounted in the lower end of the plunger 15. Upward movement of the plunger 15 causes liquid standing in the casing 10 to be drawn into the casing 16 through the intake valve 22, while downward movement of the plunger 15 causes the liquid previously drawn into the casing 16 to enter the plunger 15 through valve 23, and thereby causes liquid previously admitted into the plunger 15 to be carried upwardly in the plunger 15 and forced out of the well through the tube 12.

The structure hereinsofar described is more or less common to, or typical of, pumps of this general character and is herein set forth principally for the purpose of illustrating a form or type of pump in which the present invention is adapted to be embodied. The invention relates more specifically to the packing means within the barrel 14 which allows free reciprocatory movement of the plunger 15 in the manner above described at the same time sealing or completely separating the upper portion of the pump barrel and tube 12 from the casing 16 so that there is no flow of air or liquid between the casing 16 and upper end of the barrel 14 except through the plunger 15.

The pump barrel 14 comprises a plurality of sections 19, 21, 24, 25, 26 and 27 connected by suitable couplings 18, 20, 28, 29, 30 and 31. The plunger 15 is a straight continuous cylindrical member considerably smaller in diameter than the sections of the barrel so as to fit within the barrel with considerable clearance. The uppermost section 19 of the barrel is considerably longer than any of the other sections and is provided primarily to form a chamber or space for the sucker rod socket 17 to be carried in. The section 19 and the casing 16 are of practically the same length and are sufficiently long to accommodate the length of stroke of the plunger.

The packing for the plunger commences at the coupling 20 and continues downwardly through the barrel to its extreme lower end. The coupling 20 is formed with an inwardly extending flange 32 adapted to be between the ends of the sections 19 and 21 and formed with an opening or bore 33 adapted to more or less accurately fit the plunger 15. The plunger 15 preferably fits the bore 33 with working clearance, that is, tightly enough so that sand or foreign matter will not pass between the plunger and flange and loosely enough so that the plunger cannot, or will not, jam or become gripped in the bore. The lower surface or side 34 of the flange 32 extends straight inwardly from the main portion of the coupling to the plunger while the upper side 35 extends upwardly and inwardly from the main portion of the coupling 20 to the plun-

ger 15, causing the flange to form a more or less effective bearing for the plunger and causing it to act as a wiper or scraper to remove sand or solid matter from the surface of the plunger during its downward movement. In other words, this particular formation of the flange 32 tends to remove and direct the sand and solid matter away from the plunger and the joint between the plunger and the flange and thereby minimizes the possibility of sand entering between the plunger and the flange.

A metal ring 36 is arranged in the barrel section 21 below the flange 23, and rings of hard packing 37, preferably of leather, are arranged between the flange 32 and the metal ring 36. In practice it has been found that leather can be advantageously used as the packing 37. The ring 36 fits more or less freely in the section 21 and carries a sleeve 38 which fits around the plunger 15 with working clearance and extends considerable distance downwardly from the ring 36, as clearly shown in Fig. 2 of the drawings. The ring 36 pressed tightly against the packing 37 by a compression spring 39 arranged in the space 40 formed between the section 21 and the sleeve 38. The lower end of the compression spring seats on a ring 41 preferably of leather, which bears against, or is carried on, the upper end of reserve packing 42 carried between the lower end portions of the sleeve 38 and the section 21. The reserve packing 42 is continuous with the operative packing 43 which is just below the end of the sleeve 38 and between the section 24 and the plunger 15, as clearly shown in Fig. 2 of the drawings. From inspection of the drawings it will be noted that the section 24 has a portion 45 extending inwardly toward the plunger and having a portion fitting more or less accurately or closely around the plunger 15 and that the upper side or surface 46 of the portion 45 is curved so that the space between it and the plunger narrows from the point where the portion 45 begins, to the point where it engages the plunger. In this particular construction shown in the drawings the portion 45 actually begins at the extreme upper end of the section. From inspection of the drawings it will be seen that the lower end of the sleeve 38 does not quite extend to a point opposite the upper end of the section 24, thus causing the widest or largest portion of the packing space to be between the lower end of the sleeve 38 and the upper end of the section 24.

The reserve packing 42 between the section 21 and the sleeve 38 is compressed or held tightly between these parts and therefore will naturally swell or expand into the large space, above referred to, upon its being forced or fed downwardly by the action

of the compression spring 39. As the operative packing 43, between the lower end of the sleeve 38 and the portion 45 where it engages the plunger, wears away the reserve packing 42 is fed downwardly by the compression spring 39, expands into or fills the large space at the lower end of the sleeve 38, and as it is further fed or forced downwardly it is fed or directed inwardly or toward the plunger by the curvature of the inner wall 46 of portion 45. As will be noted from the drawings, the surface 46 of the portion 45 is curved gradually between the upper end of the section and the middle portion thereof, and forms no corners or pockets in which the packing can lodge or be caught so that it will not be properly fed to the plunger in the manner above described. In practice it has been found that good results are had when the wall 46 is curved substantially as shown in the drawings and that satisfactory results cannot be obtained if the wall 46 is merely slightly tapered at the upper end portion and sharply curved at the lower end portion.

In operation, the spring 39 causes the packing 37 to be tightly held between the ring 36 and flange 32, and holds the ring 41 tightly against the reserve packing 42 causing the operative packing 43 to be held in pressure engagement with the plunger 15. The formation of the opening which carries the packing, that is the size of the opening and also the shape of the walls of the opening, is such as to cause the operative portion 43 of the packing to bear against the plunger 15 with uniform pressure at all parts and causes the reserve packing to effectively take the place of the operative packing as it is worn away so that an effective joint is maintained. In practice when the pump is assembled the space 40 in which the spring 39 is carried is filled with oil so that the packings will be kept soft and pliable and so that the plunger will be kept properly lubricated. The ring 36 in fitting freely in the section 21 allows the sleeve 38, which fits more or less accurately around the plunger 15, to be self-centering relative to the plunger. The ring 36 being supported between the spring 39 and the packing 37 allows more or less tilting movement of the sleeve 38 and thereby allows the sleeve 38 to have endwise tilting movement in the event that the plunger 15 is temporarily flexed out of alignment. In other words, the mounting of the ring 36 and the fitting of the ring 36 and sleeve 38 is such as to allow the sleeve 38 more or less universal movement so that it will not pinch or bind on the plunger under any ordinary operating conditions. In practice, the plunger 15 is more or less continuously subjected to temporarily deformation or flexure due to the shock and vibration set up by the action of the pump.

Deformation or flexure of this character is not injurious to short bearings such as are provided by the flange 32 and by the portion 45 but they are injurious to long bearing parts such as are afforded by the sleeve 38. However, when the long bearing parts are supported in the manner provided by this invention they will move with, or be carried by, the plunger sufficiently to prevent binding or other injurious action.

In accordance with the present invention the surface 46^a at the lower side of the portion 45 extends from that portion off the portion 45 which engages the plunger to the extreme lower end of the section 24 and corresponds in curvature to the surface 46. Packing 50, similar to the packing 43, is carried between the surface 46^a and the plunger and is in connection with the reserve packing 42^a carried between the upper end portion of a sleeve 53, similar to the sleeve 38, and the section 25. The sleeve 53 extends upwardly from a ring 52, similar to the ring 36, while the reserve packing is adapted to be fed upwardly to replace the operative packing 50 by a compression spring 54 arranged in space 40^a to engage ring 41^a and ring 52. The ring 52 is carried on packing 51 which engages a flange 55, which extends inwardly from the coupling 30. From inspection of the drawing it will be seen that the arrangement and proportioning of the parts just described are substantially the same as that of the parts between the portion 45 and the flange 32 except that they are in inverted relation or arrangement. The action of the parts just described is the same as that of the parts first described.

At the underside of the flange 55 there is a hard packing 57, like the hard packings 37 and 51, held against the flange 55 by a ring 58, like the rings 36 and 52, pressed upwardly by spring 59, like springs 39 and 54. The ring 58 carries a downwardly extending sleeve 60, while the spring 59 presses downwardly on reserve packing 61 which is continuous with operative packing 62 carried between the plunger 15 and the inner wall 63 of the portion 45^a of section 27. The packing apparatus between the flange 55 and the section 27 is identical in all respects with that between the flange 32 and portion 45 of section 24.

From the foregoing description it will be understood how there are preferably three distinct sets of soft packings, two fed downwardly by spring action and one fed upwardly by spring action, and it will be understood how each of the packings operates in the same manner.

In practice this arrangement of packings herein set forth is particularly effective and durable. Liquid or air to leak past the plunger and barrel must pass the flange 32, the hard packing 37, the packing 43, the

portion 45, the packing 50, the hard packing 51, the flange 55, the hard packing 57, the packing 62, and the portion 45^a. It is obvious that such leakage is practically impossible if the various parts just enumerated are in proper working condition. By the construction and arrangement provided by the invention the necessary parts will operate properly and effectively when in good condition and will remain in good operative condition for a long period of time under ordinary working conditions.

Having set forth only a preferred embodiment of my invention I do not wish to specifically limit myself to the details herein set forth but wish to reserve to myself any changes or modifications which may appear to those skilled in the art or which may fall within the scope of the following claims.

Having described a preferred form of my invention, I claim:

1. In a pump of the character described embodying a barrel and a plunger therein, packing means between the barrel and plunger comprising, a stationary member carried by the barrel between it and the plunger, a ring around the plunger and within the barrel, packing around the plunger between the stationary member and the ring, an extension on the ring extending around the plunger and through the barrel, active packing around the plunger beyond the end of the extension, reserve packing around the extension and adjacent to the active packing, and means between the extension and the barrel to press the ring against the first mentioned packing and to press the reserve packing toward the active packing.

2. In a pump of the character described embodying a barrel and a plunger therein, packing means between the plunger and the barrel comprising, an inwardly extending member on the barrel, a ring around the plunger within the barrel, said ring fitting the barrel and plunger with clearance, packing between the barrel and the plunger and between the inwardly extending member and the ring, a sleeve like extension on the ring extending around the plunger and through the barrel, a part on the barrel beyond the end of the extension extending inwardly toward the plunger, active packing around the plunger between the end of the extension and said part, reserve packing around the end portion of the extension and continuous with the active packing, and a spring at the extension and under compression between the ring and reserve packing.

3. In a pump of the character described embodying a barrel and a plunger therein, packing means between the plunger and the barrel comprising a flange extending in-

wardly from the barrel to fit the plunger with clearance, a ring fitting in the barrel and around the plunger with substantial clearance, hard packing between the barrel and the plunger and between the flange and the ring, a sleeve extending from the ring through the barrel and around the plunger, the sleeve fitting this plunger with working clearance, an inwardly extending portion on the barrel beyond the end of the sleeve shaped so that the space between it and plunger decreases in width from the end of the sleeve to a point where said portion fits the plunger with working clearance, active packing in said space, reserve packing around the end portion of the sleeve continuous with the active packing and adapted to replace the active packing, and a compression spring around the sleeve and between the ring and the reserve packing.

4. In a pump of the character described embodying a barrel and a plunger therein, packing means between the barrel and plunger comprising a sleeve fitting around the plunger with working clearance and within the barrel with substantial clearance, an inwardly extending part on the barrel, said part starting at a point immediately beyond one end of the sleeve and being shaped so that the space between it and the plunger decreases in width in a direction away from the sleeve to a point where said part fits the plunger with working clearance, packing between the sleeve and the barrel and extending between said part and the plunger, and means for feeding the packing from between the sleeve and the barrel to replace packing worn away by the plunger.

5. In a pump of the character described embodying a barrel and a plunger therein, packing means between the barrel and plunger comprising a sleeve fitting around the plunger with working clearance and within the barrel with substantial clearance, means for yieldingly holding the sleeve stationary relative to the barrel, an inwardly extending part on the barrel, said part at a point immediately beyond one end of the sleeve and being shaped so that the space between it and the plunger decreases in width in a direction away from the sleeve to a point where said part fits the plunger with working clearance, packing between the sleeve and the barrel and extending between said part and the plunger, and a spring around the sleeve to feed the packing from between the sleeve and the barrel to replace packing worn away by the plunger.

6. In a pump of the character described embodying a barrel and a plunger therein, packing means between the barrel and plunger comprising a sleeve fitting the plunger with working clearance and the

barrel with substantial clearance, a part
extending inwardly from the barrel to the
plunger at a point spaced from one end of
the sleeve, active packing around the
5 plunger between the end of the sleeve and
said part, reserve packing around the sleeve
and adjacent the active packing, and means
for feeding the reserve packing to take the

place of the active packing as it wears
away.

In witness that I claim the foregoing I
have hereunto subscribed my name this 26th
day of October, 1920.

GEORGE W. WRIGHT.

Witness:

VIRGINIA BERNINGE.
